United States Patent Office.

WILLIAM K. VANDERSLECE AND LUCIUS THOMPSON, OF SAN FRANCISCO, CALIFORNIA.

Design No. 3,402, dated March 2, 1869.

DESIGN FOR A SPOON OR FORK-HANDLE

The Schedule referred to in these Letters Patent and making part of the same.

To all whom it may concern:

Be it known that we, WILLIAM K. VANDERSLECE and LUCIUS THOMPSON, of the city and county of San Francisco, State of California, have originated and discovered a new and original Design for Table-Service; and we do hereby declare that the following is a full and exact description of the said design, reference being had to the accompanying photograph or drawing, showing the design as applied to a table-fork.

The front design, marked Figure 1, consists of a series of marginal lines, *a a*, forming a border along the sides of the handle, meeting in a folding design, *b*, in the centre, from which depends a pointed line, *c*, with raised figures near the point, surmounted by an open flower-cup, *d*.

The upper end of the handle bears the figure of a tiger's face, *A*, with small festoons encircling it, the marginal lines being wider apart near the face, and having diagonal lines passing from one to the other, as shown.

A creased folding-device, *e*, clasps the two lines at the point where the diagonal lines cease.

The marginal lines, on each side, end at the bottom in a drop, at the point *f*, having a smaller drop in the centre, and directly above these is a design, *g*, bearing three prongs, which point upward.

The design marked Figure 2 is the back of the fork, and is much the same as fig. 1, except that instead of

the folding-device in the middle of the handle, the marginal lines on the upper part of the handle, at that point, meet in a curve at *h*, and depending from it is a three-pronged device, similar to *g*, described as pointing upward from the lower part of fig. 1, the lower marginal lines meeting over the curved end in any desired form.

Instead of the tiger's face, on the upper end of the handle, are three figures, *i i i*, radiating from a point, their bases pointing downward, the inner marginal lines on each side forming a curve, and ending in a drop on each side of the middle figure *i*.

On fig. 2, the diagonal lines are omitted.

This design is intended to be used in an entire service, the same general features or designs running through the entire set.

Having thus described our design,

What we claim, and desire to secure by Letters Patent, is—

The design or pattern for table-service, herein set forth.

In witness whereof, we have hereunto set our hands.

WILLIAM K. VANDERSLECE.
LUCIUS THOMPSON.
